UNITED STATES PATENT OFFICE.

WILLIAM SCHMID, OF COLDWATER, MICHIGAN, ASSIGNOR TO CASKEY-DUPREE MANUFACTURING COMPANY, OF COLDWATER, MICHIGAN, A CORPORATION OF OHIO.

COMBINED LIGHTING AND IGNITION SYSTEM FOR AUTOMOTIVE VEHICLES.

Application filed November 22, 1924. Serial No. 751,638.

My invention relates to switches and to ignition and lighting systems of automobiles or other automotive vehicles employing the same.

5 In automobile ignition and lighting systems, locks are employed to open and close the ignition circuits without disturbing the operability of the lighting circuits. In one general type of prior equipment, ignition locks have been accessible through the switch handles that were always free to control the lighting circuits, the keys themselves constituting a form of switch handle for the ignition switches, the handles operating independently of the keys and the keys independently of the handles. The prior devices are thus essentially double switches, each operable independently of the other.

Each of the circuits controlled by the switch of my invention has complementary contacts included in the formation of the switch, a single switch operating handle being common to the circuits and adapted to be in controlling relation to their complementary contacts, sets of contacts pertaining to different circuits being arranged in physical succession to be adapted for control in succession by the handle as it is swept through its range of movement. I preferably keep only the 20 parking light circuits always within the control of the switch handle. I include the ignition and main head light circuits within the control of this handle or lock these latter two circuits from the control of the handle, as desired, but without disturbing the 25 control of the parking circuits by the handle. The handle thus constitutes a single switch element always in control of the parking light circuits, this handle being placed in or out of control of the ignition and main head light circuits according to the condition 30 of the lock. The main head light circuit can not thus be closed when the ignition is locked. The battery current can not then be wasted, 35 nor will there be the objectionable head light glare when the automobile is parked.

In the preferred embodiment of the invention, the key is passed through the handle of the lock and the lock is housed in an axial 40 or hub portion of the handle, but the invention is not to be thus restricted. When the lock is closed by the key, it serves to eliminate the ignition and main head light circuits from the control of the handle without disturbing the handle's control of the

parking circuits. When the lock is opened, the handle may have control of all circuits.

In accordance with my present invention, this result is effected by means of a lock which, when open, permits movement of the 60 handle throughout its range in which all circuits may be controlled by the handle. When the lock is closed, the range of movement of the handle is mechanically reduced to permit the handle to retain control of the 65 parking light circuits only, the lock then preventing the handle from moving to the contacts pertaining to the ignition and main head light circuits. While the switch is then limited to control of the parking light 70 circuits, I do not wish to be limited to the character of the lighting circuit or circuits then controlled by the handle. I prefer to employ supplemental head lamps to furnish the front parking light, and other supplemental head lamps for furnishing the 75 dimmed head lights, but the invention is not to be thus limited, it being common to establish dimming parking and dimming front head light circuits through the same head 80 lamps that are also employed to furnish bright illumination.

The invention will be more fully explained in connection with the accompanying drawings in which Fig. 1 is a rear or bottom view 85 of the switching mechanism of my invention as it is preferably constructed; Fig. 2 is a sectional view on line 2—2 of Fig. 1; Fig. 3 is a sectional view on line 3—3 of Fig. 2; Fig. 4 is a sectional view on line 90 4—4 of Fig. 2; Fig. 5 is a sectional view on line 5—5 of Fig. 3; Fig. 6 is a front view on a reduced scale; Fig. 7 is a sectional view on line 7—7 of Fig. 5; and Fig. 8 is a diagram showing one arrangement of 95 circuits and the switching mechanism of my invention as it is preferably related thereto.

The circuit controlling handle 1 has a hub portion 2 formed with wings or flanges 3 at its circular base or inner end 4. This circular hub base is freely received within a circular opening 5 formed through and coaxial with the mounting and escutcheon plate 6 that has openings 7 by which it and the switch assembled therewith may be 100 mounted upon an automobile dash board or other support. The cylindrical switch casing 8 is assembled coaxially with and behind the plate 6 by means of rivets 9, the outer or front end wall 10 of the casing being 110

depressed to afford a narrow space in which the wings or flanges 3 of the handle may freely move when the handle is turned upon the axis defined by the circular edge of the opening 5. A rotatable contact actuator 11, preferably a ring of insulating material, is assembled with the inwardly extending continuations 12 of the hub 2 that enters recesses 11' in ring 11, this actuator being located within the casing between the outer end wall 10 of the casing and the insulating contact carrying disc 13 which closes the inner end of the casing. A rotatable contact carrier 14 shown in the form of a metallic ring, is interposed between the elements 11 and 13. The ring carries contact buttons 16, 17, 18, 19, engageable with certain of the contacts 20, 21, 22, 23, 24, 25, 26, 27, 28, 29 pertaining to the different handle controlled circuits and which are provided upon the contact carrier 13 and are positioned to be engageable at the inner face of this carrier. The buttons 16, 17, 18, 19 have spring barrel extensions upon the other side of the carrier 14, these spring barrels housing springs 30 which press plungers 31 into recesses formed in the ring 11. The handle, when turned, will turn the ring 11 and the ring will turn the contact carrier 14 through the intermediation of the plungers 31. The lock includes a barrel 32 that may be turned within a cylindrical housing 33 that is fixed upon and projects outwardly from the casing wall 10 and extends into the hub or axial portion of the handle. The lock barrel has a reduced outer end 34 upon which the outer end of the hub of the handle is journaled. The lock illustrated also includes key controlled tumblers 35 which are self-projected into one of the lateral openings 36 in the housing 33 upon the withdrawal of the turned key 35' when it is desired to mechanically reduce the range of movement of the handle to limit the handle to control of the parking light circuits, the ignition and main head light circuits being then locked open. When the tumblers are projected into an opening 36, the lock barrel in being turned by the key to secure this result operates the cam pin 37 thereon to shift one end of the slide 38 outwardly, the slide having a cam slot 39 which receives and is angular to the line or bodily movement of the pin. The slide is limited to diametrical movement by the guiding ears 41 carried by the casing end wall 10. When the slide is outwardly projected upon closing the lock, its outermost end enters the arcuate recess 42 in the carrier 11. This recess is commensurate with that portion of the range of movement of the handle in which the handle opens and closes the parking light circuits and is just long enough for this purpose and short enough to prevent the movement of the handle into that portion

of its range of movement in which it could otherwise control the ignition and main head light circuits. When the tumblers are drawn entirely within the lock barrel when the lock is opened, the handle will continue its control of the parking light circuits and will then also have control of the ignition and main head light circuits. The key is thus used either to lock the handle out of control of the ignition and main head light circuits or to place these circuits in the control of the handle to relieve the key of the duty of controlling these circuits, the handle always remaining in control of the parking light circuits.

The preferred arrangement is diagrammatically illustrated in Fig. 8. The internal combustion hydrocarbon engine 43 is in driving relation to the automobile or other automotive vehicle and also to the generator 44 that is in charging relation to the storage battery 45, the generator also supplementing the battery as a source of current, all as is well known. The engine also operates an interrupter 46 which is included in an inducing ignition circuit arranged to be supplied with current from the battery or generator and which includes the primary or inducing winding 47 having one terminal connected with the arcuate contacts 20, 21 and its other terminal grounded through the interrupter and also through the condenser 48 that are in shunt relation. The engine also operates the timing switch 49 whose switch arm is in the induced ignition circuit that contains the induced winding 50, as is understood. The main bright head lamps 51 and 52 are in parallel, being connected by the common conductor 53, with the contact 22. The front parking head lamps 54, 55 are in parallel, being connected by a common conductor 56 with the contact 23. The dimming main head lamps 57, 58 are connected by a common conductor 59 with contact 24. The usual tail light 59, also available as a rear parking lamp, is connected with the contacts 25 and 26. The battery and generator are permanently connected with the contacts 27, 28 and 29. The engagement between the ring contacts and contacts 24, 25, and 29, which pertain only to the parking lamps 54, 55, 59 is not lock controlled.

When the switch is in "Off" position, all circuits controlled thereby are open. The lock is then usually thrown to enter the slide 38 into the arcuate recess 42 in the ring 11 so that this ring and the carrier 14 can only be moved by the handle through a reduced range permitting the handle to control the parking lights only, the ignition, main and dimming head lamp circuits being thus locked open.

When the switch is placed in "Day" position, none of the lighting system contacts is

in circuit, the ring 14 having then no connection therewith. The ignition circuit is, however, controllable by the handle, the lock being open.

5 When the switch is in "Park" position, all the front and rear parking circuits are controllable by the handle, but the ignition and the head light circuits are locked open against control by the handle.

10 If the switch is in "Dim" position, circuits through lamps 57, 58, 59 are closed but the other lighting circuits are opened. The ignition circuit is controllable by the handle, however, the lock being open.

15 If the switch is thrown to "Bright" position, circuits through lamps 51, 52 and 59 are closed but the other lamp circuits are opened. The ignition circuit is controllable by the handle in this adjustment, the lock 20 being open.

In some systems, the front parking illumination is effected by a dimming of the head lamps and without employing supplemental head lamps. I do not, therefore, wish to be 25 limited to the employment of supplemental

head lamps in the front parking light circuit, nor do I wish to be limited to the character or purpose of the light circuits which, with or apart from the ignition circuits are controlled by the switch handles.

30

Changes may be made without departing from my invention.

Having thus described my invention, I claim:

An electric switch including a casing, a 35 rotatable contact actuating ring within said casing, the inner peripheral face of said ring having a recess formed therein providing a pair of spaced stop shoulders at the ends thereof, a member located within said 40 ring and mounted on said casing for movement into and out of said recess whereby the ring has limited rotary movement when said member is disposed within said recess, and a lock controlling the movement of said 45 member.

In witness whereof, I hereunto subscribe my name.

WILLIAM SCHMID.
